UNITED STATES PATENT OFFICE.

HARRY JAMES WILTON, OF VANCOUVER, BRITISH COLUMBIA, CANADA.

BUCKLE.

1,260,844.

Specification of Letters Patent. Patented Mar. 26, 1918.

Application filed September 24, 1917. Serial No. 192,970.

To all whom it may concern:

Be it known that I, HARRY JAMES WILTON, a citizen of the United States of America, and a resident of Vancouver, in the Province 5 of British Columbia and Dominion of Canada, have invented new and useful Improvements in Buckles, of which the following is a specification.

My invention is an improvement in buckles, and has for its object to provide a buckle especially adapted for connecting the ends of a belt, wherein the buckle is formed of resilient material, shaped to form an open loop, one end of which is engaged by 10 one end of the belt, the other end of the loop having means for clasping the other end of the belt.

In the drawings:

Figure 1 is a front view of the improved 20 buckle, showing it in engaging position;

Fig. 2 is a side view;

Fig. 3 is a section on the line 3—3 of Fig. 1;

Fig. 4 is a front view of the buckle 25 detached;

Fig. 5 is a front view of a different arrangement of the invention.

In the embodiment of the invention shown in Figs. 1 to 4, the buckle is formed of resilient wire, bent upon itself to form a loop 30 open at one end. The said loop comprises a body 1 to which one end 2 of the belt is permanently fixed, and arms 3 extend laterally from the body. Each of these arms at 35 the end remote from the body is bent inwardly, as indicated at 4, to lie alongside the inwardly bent portion of the other arm and then outwardly, as indicated at 5, to form a substantially U-shaped member at 40 the outer end of each arm. These U-shaped members interengage as shown, the portion 4 of one arm lying beneath the portion 4 of the other, while the portion 5 of the said arm overlies the portion 5 of the other arm. 45 The extremity of each portion 5 is bent backwardly upon itself, as indicated at 6, to form a rounded blunt portion that will not injure the wearer or the belt.

The other end 7 of the belt is adapted to 50 be passed through the U-shaped portion of

both arms, and it will be evident that when the said portions are moved away from each other, as shown in Fig. 4, the belt will be clasped between the bodies of the U-shaped portions to firmly hold the same.

55

In use, the end 7 of the belt is passed between the arms of the U-shaped portions, so that the edges of the belt are in engagement with the bodies of the U-shaped portions, the said portions, during the insertion of the belt end, being moved in a direction to cause the bodies of the U-shaped portions to move outwardly from each other by pressing inwardly upon the arms 3, that is, by pressing the said arms toward each other. It will be 60 noticed that each arm 3 has an outwardly offset portion 8 at the junction of the arm with the portion 4, these offset portions 8 forming finger pieces for permitting the easy compression of the buckle to release or 65 engage the belt end.

In the embodiment of the invention shown in Fig. 5 the buckle is a double buckle having a clasp for each end of the belt. In this construction the bodies 9 of the buckle are 70 twisted together, as shown, to form a single cross bar, and the arms 10 of the said bodies extend in opposite directions. Each arm is provided at the end remote from the body with a substantially U-shaped member 11, 80 and the said members interengage as described for the U-shaped members in Figs. 1 to 4. With this construction both ends of the belt may be clasped by the buckle, in the same manner as the one end is clasped in the 85 construction of Figs. 1 to 4.

I claim:

A buckle comprising a resilient substantially U-shaped member consisting of a body and arms extending laterally from the body, each arm having at the end remote from the body an open loop, each loop extending transversely of the plane of the buckle and opening outwardly, said loops having their corresponding side members crossed.

HARRY JAMES WILTON.
